UNITED STATES PATENT OFFICE.

LAWRENCE A. MERK, OF WILKINSBURG, PENNSYLVANIA, ASSIGNOR OF ONE-HALF TO
EDWIN RUUD, OF PITTSBURG, PENNSYLVANIA.

GAS-PRESSURE REGULATOR.

977,820.

Specification of Letters Patent.

Patented Dec. 6, 1910.

Application filed May 31, 1907. Serial No. 376,475.

To all whom it may concern:

Be it known that I, LAWRENCE A. MERK, a resident of Wilkinsburg, in the county of Allegheny and State of Pennsylvania, have 5 invented certain new and useful Improvements in Gas-Pressure Regulators, of which the following is a specification.

This invention relates to that type of gas pressure regulators commonly used with gas 10 engines wherein the suction of the charging stroke automatically opens a gas inlet valve, with means for holding the valve normally closed.

The primary object is to provide a valve 15 which may be readily removed, being unattached to the diaphragm or other suction-operated valve-actuating means and making it unnecessary to disturb the same when removing the valve, its most frequent removal being 20 for the purpose of cleaning the regulator or the valve itself. As is well known, producer gas contains many impurities, both liquid and solid, and when such gas is used frequent cleaning of the regulator is necessary. With 25 the structure herein proposed, the valve may be readily removed without disturbing the diaphragm, thus greatly simplifying the cleaning operation.

In the accompanying drawings, Figure 30 1 is a vertical sectional view of a regulator constructed in accordance with the invention, and Fig. 2 is a similar view of a portion of the same, showing the admission valve open.

Referring to the drawings, the regulator 35 casing 2 is of shell-like form, with the open top of its main or suction chamber 3 closed by diaphragm 4 and the casing cover or top 5. Chamber 3 connects at 6 with the engine 40 or other apparatus supplied through the regulator. The central lower portion of casing 2 is partitioned to form the annular inlet chamber 7, to which extends the gas inlet passage 8, said chamber being open at 45 its top at 9 for the passage of gas into chamber 3. The bottom of said chamber is open at 10 to communicate with the depending settling chamber 11, and the under faces of the walls of openings 9 and 10 form seats

9' and 10', respectively, for the downwardly 50 opening double or balanced valve 12, the latter having the central downwardly extending stem 13.

The bottom 14 of chamber 11 is removable and carries the central guide 15 for stem 13. 55 Beneath this guide the stem is engaged by spring 16 supported by the spider-like extension 17 of bottom 14, with screw 18 for regulating the tension of the spring and the consequent resistance of valve 12 to low- 60 ering and opening.

Carried by diaphragm 4 is depending stem 19 which moves in the fixed guide 20, arranged centrally above valve 12, with the lower extremity of stem 19 adapted to bear 65 upon the upper extremity of valve-stem 13. Stem 19 is extended upwardly through casting top 5, as indicated at 19', and a central balancing spring 21 may be arranged above the diaphragm which may operate in connection with spring 16 for facilitating and adjusting the tension of the valve to the pressure required to open it, as will be understood. The drain or outlet 22 of chamber 11 may be looped as shown to provide 75 a water seal.

The operation will be apparent. The suction created in chamber 3 by the charging stroke of the engine will cause the diaphragm to lower under atmospheric pressure and the pressure of stem 19 will open the valve and admit the required amount of gas, the diaphragm raising and the valve closing when the charge has entered. To 80 remove the valve for cleaning it or the regulator casing, it is only necessary to detach bottom 14 of the settling chamber and the valve may be withdrawn and ready access 85 had to the interior of the regulator. The diaphragm remains in place and is in no 90 wise disturbed when the valve is thus removed.

I claim:

A gas regulator comprising a casing having a suction chamber provided with a double seated gas inlet, a tubular balanced valve for the inlet whereby the gas entering through one of the valve seats passes di-

rectly to the suction chamber and that entering through the other seat passes to the suction chamber through the valve, a diaphragm within the suction chamber and operatively connected to the valve for opening the same, and spring means for holding the valve normally closed.

In testimony whereof I affix my signature in presence of two witnesses.

LAWRENCE A. MERK.
